UNITED STATES PATENT OFFICE.

ROY W. WEIR, OF HAMMOND, INDIANA, ASSIGNOR TO MARVEL COMPANY, OF HAMMOND, INDIANA, A CORPORATION OF OHIO.

SUCTION SWEEPER.

Application filed July 25, 1919. Serial No. 313,228.

To all whom it may concern:

Be it known that I, Roy W. Weir, a citizen of the United States, residing at Hammond, in the county of Lake and State of Indiana, have invented a certain new and useful Improvement in Suction Sweepers, of which the following is a specification.

My invention relates to improvements in suction sweepers and has for one object to provide a new and improved form of hand operated suction sweeper, particularly of the type wherein a fan is used to suck up dust laden air and discharge it into a bag.

Another object is to combine with such a suction sweeper an electric motor which, at the option of the operator, may be used to drive the fan or may be left entirely out of operation so that the sweeper may be used as a hand sweeper or as an electric sweeper.

In the particular form illustrated herewith, I have shown in connection with the fan, a motor of the single phase induction type in which the rotor is secured to the non-magnetic top of the fan and the stator is secured to the top of the suction cleaner casing.

Sweepers of this hand propelled type have been used before wherein there was a train of gears between the supporting axle and the fan whereby a forward movement of the housing would cause a rotation of the supporting wheels and thus drive the fan, the rear movement leaving the fan and gear train free to go forward because it was connected through an overrunning or ratchet clutch. Experience has, however, shown that an apparatus of this type, wherein the overrunning clutch was between the gear train and the axle, as has been the past practice, was not satisfactory because it made it necessary for the fan to carry the gear train with it as it ran forward, dissipating a large proportion of the stored energy on the return stroke. The result was that, owing to the friction of the gear train, the fan decelerated too rapidly and the suction during the return stroke was very much too low. Owing to the delay while the fan speeded up on the forward stroke, it was too low there also. By my invention, I provide a free fan which stores energy on the forward stroke and which is disconnected altogether from the balance of the mechanism on the

return stroke and thus is able to apply all its stored energy to the work of drawing in 55 the dust laden air.

So far as I am aware, no combination has ever been previously made in a suction sweeper of alternate motor driving and hand driving means which may be used separately.

My invention is illustrated more or less diagrammatically in the accompanying drawings, wherein

Figure 1 is a bottom view with the driving gear cover removed;

Figure 2 is a vertical section on the line 2-2 of Figure 1;

Figure 3 is a horizontal section on the line 3-3 of Figure 2;

Figure 4 is a horizontal section on the line 4-4 of Figure 2;

Figure 5 is a vertical section on the line 5-5 of Figure 1.

Like parts are indicated by like characters 75 throughout.

A is a suction casing with a suction nozzle A¹ which has a suction inlet A² with a brush A³ mounted for rotation therein in any suitable way. Leading to the fan casing in 80 the rear is the passage A⁴. Adjacent the center of the brush is the pulley A⁵, adapted to be surrounded and rotated by the belt A⁶ which enters the bottom of the suction inlet through the slit A⁷. It is driven by 85 the pulley B on the wheel B¹ which is rotated by contact with the surface to be cleaned, which it engages by the two rims B², B³ surrounding the pulley B and preferably surfaced with rubber or other frictional material. The wheel and the pulley are mounted on the yoke B³ which is pivoted at its front on the underside of the nozzle casing. The opposite end of the yoke is engaged by the set screw B⁴, the rotation of 95 which adjusts the height of the wheel and thus of the suction nozzle. The suction casing in its rearward extension forms a relatively flat platform C on which is mounted the fan casing C¹. The fan C² is mounted 100 therein on the vertical shaft C³. The passage A⁴ leading from the suction nozzle surrounds the axis of the fan having a substantially horseshoe shaped inlet A⁹ into the bottom of the fan chamber. The fan shaft penetrates the platform C and projects down 105

into the gear housing D beneath it, and is journaled at D¹. The housing D has a removable housing cover D² intermediate its ends; within this housing the shaft C³ carries 5 the gear D³ in engagement with the gear E on the stub shaft E¹ journaled in the bottom of the plate C. Beneath the gear E is the bevelled pinion E² in engagement with the bevelled gear F on the shaft F¹ which penetrates 10 the gear housing and is rotatably supported in the lugs F², F² depending from platform C. The shaft carries the wheels F³, F³ on which the suction casing is supported, these wheels being preferably surrounded by frictional rings F⁴, F⁴ of rubber or other suitable material. Within the gear F is a roller ratchet comprising the indentations F⁵, F⁵ on the inside of the gear, the rollers F⁶, F⁶ therein and the springs F⁷, F⁷ adapted to 15 keep the rollers seated against the bearing surface F⁸ on the shaft F¹. When the machine is pushed forward, by the inclination of the ratchet the rollers engage the bearing surface on the shaft and the ratchet bearing 20 surface on the inside of the gear and the gear rotates with the shaft, taking its rotation from the friction of the wheels F³, F³ on the floor. When the machine is drawn backward or stopped, the rollers are pushed 25 out against the springs but the springs keep them in constant contact with the bearing surface so that the clamping action, when the direction is reversed or forward movement stopped, is almost instantaneous. The upper 30 end of the fan shaft C has milled in it the flute member G and within the flutings are positioned the ratchet rollers G¹, G¹. The fan socket G² engages the ratchet rollers but is out of contact with the ratchet member and is supported by the ball bearing G⁴ 35 mounted in the socket at the top of the ratchet member and the ball bearings G⁵, G⁵, at its top and bottom. It will be understood, of course, that this disposition of ball bearings might be varied. It is essential 40 only that the fan rotate as freely as possible. When the machine is pushed forward the clutch within the fan socket drives the fan. The instant that forward acceleration 45 ceases, the ratchet clutch automatically breaks its connection and the fan rotates freely on the ball bearing, utilizing all of its force and momentum in maintaining its own speed. Mounted on the depending lugs F², F² are the projecting studs 50 or screws H, H on which the ends of the handle bail H¹ are rotatably mounted. The studs H, H are so positioned that when the handle bail is in a horizontal position it 55 rests on the shaft F¹. When the handle bail is upright or tilted slightly forward, it is supported by the projections H², H² from the casing. The handle H³ of any suitable type is mounted in the handle bail and is 60 adapted to support the end of a dust bag 65

which is not here shown. The inner end of such a bag is clamped or otherwise fastened about the outlet end I of the fan casing. Mounted on the non-magnetic top J of the fan C² is the rotor K of an induction motor. It is built up of the copper rings K¹, K¹ and between them a plurality of iron rings K², K², the whole is secured to the top of the fan and fastened together by the copper rivets K³, K³. This rotor is, of course, integral with and moves with the fan. Secured to the top of the fan casing is a stator L of the motor. It is built up of a plurality of plates L¹, L¹ and has about its center the coil L² which is connected with the plug in the electric connection L³ to which is connected the electric conduit L⁴. 70 75 80 85

It will be understood that while I represent an operative device, the parts and arrangement of parts may be varied in many ways without departing from the spirit of my invention and I wish, therefore, that my drawings be regarded as in a sense diagrammatic. 90

The use and operation of my invention when it is desired to drive the suction 95 100 105 110 115 120 125 130

sweeper by hand are as follows:— The housing or truck is supported on wheels as shown. These wheels are preferably rubber tired so that there will be a strong frictional connection between them and the floor or floor covering. The nozzle carried by the housing or frame work extends down close to the floor covering, and there is a suction passage leading from it to the fan chamber. There is a gear train enclosed within a dust tight housing and leading from the axle to the fan and driving it. The fan discharges the dust laden air through a passage into a dust bag supported partially on the housing and partially on the operating handle, whereby the dust is separated out of the air and the material picked up from the carpet is retained, while the air passes on. 100 105 110 115 120 125 130

The overrunning clutch is located within the fan hub so that the gear train works back and forth as the apparatus moves back and forth across the floor. This possibly makes the machine a little heavier to push on the return stroke but the resistance is negligible compared with the resistance to the movement of the apparatus itself, across the floor, and a great advantage accrues in that the fan is thus permitted to rotate freely and without having to carry the gear train with it. Thus it keeps its speed and does effective cleaning on the return stroke as well as on the forward stroke, and experience shows that it maintains, at all times, a speed sufficiently high to do effective cleaning. Since the friction gear itself is not driven on the back stroke, wear and tear is reduced, and the weight of the stroke required is lessened. 130

The use and operation of my invention when it is desired to use the motor driving means, are as follows:

As the motor illustrated herewith has no starting torque, if the current is turned on when the cleaner is stationary, it will not rotate the fan. It will, however, drive the fan in either direction and it requires only a small initial thrust to start it, after which it will revolve at a high rate of speed and will produce sufficient suction for all cleaning purposes. In order to use the motor driven feature, the current is turned on and the sweeper is pushed forward slightly. This is sufficient to start the motor, when it will revolve of its own accord irrespective of the motion of the sweeper and the sweeper may then be used exactly like any other motor driven sweeper.

Although I have illustrated a particular type of electric motor, it is, of course, obvious that other types may be used and I do not wish to be limited to the particular type shown, as the principle of my invention applies equally well to a sweeper wherein there is a combination of the hand driving means with the motor driving means in which any other type of electric motor is used.

I claim:

1. In a suction cleaner a fan chamber, a fan therein comprising a flat circular plate with fan blades downwardly depending therefrom, an electric motor located within the fan chamber, the rotor of the electric motor being rigidly mounted on the outer periphery of the plate on the side opposed to the fan blades.

2. In a suction cleaner a fan chamber, a fan therein comprising a flat circular plate with fan blades downwardly depending therefrom, an electric motor located within the fan chamber, the rotor of the electric motor being rigidly mounted on the outer periphery of the plate on the side opposed to the fan blades, the stator of the motor being located immediately above the plate within the rotor.

3. In a vacuum cleaner a fan, an electric motor having its rotor integral with the fan, an overrunning clutch associated with the fan, supporting wheels for the cleaner and means for driving the fan through said wheels and said overrunning clutch.

4. A suction cleaner comprising a fan and an electric motor which motor has no starting torque, together with means manually controlled by the operator for starting the motor, the starting means comprising driving and supporting wheels and an overrunning clutch interposed between them and the fan whereby a movement of the machine starts the rotation of the fan.

5. In a suction cleaner, the combination with the casing thereof, and a fan located therein, of a motor associated directly with

said fan for power operation thereof, manually-operated means geared to the fan for driving the latter independently of its power operation, and a driving connection included in the gearing between the fan and the manually-operated driving means for rendering the fan operable alternatively by the motor or the manually-operated means.

6. In a suction cleaner, the combination with the casing thereof, and a fan located therein, of a motor associated directly with said fan for power operation thereof, manually-operated means geared to the fan for driving the latter independently of its power operation, and an over-running clutch included in the gearing between the fan and the manually-operated driving means for rendering the fan operable alternatively by the motor or the manually-operated means.

7. In a suction cleaner, the combination with the casing thereof, and a fan located therein, of a motor associated directly with said fan for power operation thereof, said motor having no starting torque, manually-operated means for driving the fan and initiating a torque in said motor, and a driving connection included in said manually-operated means and serving to disconnect the fan from the manually-operated means when operation of the motor has accelerated to a predetermined point.

8. In a suction cleaner, the combination with the casing thereof, and a fan located therein, of a motor associated directly with said fan for power operation thereof, said motor having no starting torque, manually-operated means for driving the fan and initiating a torque in said motor, and an over-running clutch included in said manually-operated means and serving to disconnect the fan from the manually-operated means when operation of the motor has accelerated to a predetermined point.

9. In a suction cleaner, the combination with the casing thereof, and a fan located therein, of a motor associated directly with said fan for power operation thereof, said motor having no starting torque, the rotor of said motor being mounted upon and operating with the fan, and the stator of the motor being mounted upon the cleaner casing, manually-operated means geared to the fan for driving the latter and for initiating a torque in the motor, and a driving connection included in said manually-operated means for disconnecting the fan from the latter when the speed of the motor is accelerated to a predetermined point.

10. In a suction cleaner, the combination with the casing thereof, and a fan located therein, of a motor associated directly with said fan for power operation thereof, said motor having no starting torque, the rotor of said motor being mounted upon and operating with the fan, and the stator of the

motor being mounted upon the cleaner casing, manually-operated means geared to the fan for driving the latter and for initiating a torque in the motor, and an over-running 5 clutch included in said manually-operated means for disconnecting the fan from the latter when the speed of the motor is accelerated to a predetermined point.

In testimony whereof, I affix my signature in the presence of two witnesses this 10 23rd day of July, 1919.

ROY W. WEIR.
